COUNTING DEVICE

James W. Bryce, Glen Ridge, N. J., assignor to
 International Business Machines Corporation,
 New York, N. Y., a corporation of New York

Application April 15, 1937, Serial No. 136,965

7 Claims. (Cl. 235—92)

This invention relates to improvements in counting devices and has for its principal object the provision of electromagnetically operated operating mechanisms which are particularly adapted for very high speed machine operations.

It has been found that the standard counting devices, such as the regular Veeder counter, when controlled by electromagnetic mechanisms usually are incapable of registering extremely high

speed machine operations due to the timed interval required to energize the counter magnet sufficiently to actuate the counter. To overcome this objection, it has been proposed to provide a series of individual high speed relays which are

responsive to the control impulses generated in extremely short intervals of time. The individual relays are, in effect, transfer relays and are successively operated in such a manner that for each impulse energizing the circuit control-

ling the series of relays, one relay is energized to indicate the number of the impulse impressed upon the chain of relays and at the same time condition associated circuits so that the next impulse is effective to energize the next relay in

the chain.

In the proposed manner, a number of the said high speed relays may be energized in succession and upon reception of a predetermined impulse, for example, every tenth or twentieth impulse, a standard Veeder or similar counter can be actuated, thereby causing an entry into the standard counter and re-conditioning the series of high speed relays for a similar counting cycle.

Therefore, further objects of the present invention are the provision of a plurality of high speed relays successively operated upon successive reception of the control impulses which may be indicative of completed cycles of certain machine operations, or the passage of articles by a predetermined point or the like; the provision for effecting visible registration upon reception of predetermined impulses indicating the number of machine operations completed or the number of articles which passed the predetermined point; the provision of automatically re-conditioning the chain of high speed relays for further operation upon reception of a predetermined impulse; the provision of successive entry from one series of high speed relays to another series and automatically conditioning the first series for further reception of the control impulses.

Various other objects and advantages of the invention will be obvious from the following particular description of one form of mechanism

embodimenting the invention or from an inspection of the accompanying drawings; and the invention also constitutes certain new and useful features of construction and combination of parts hereinafter set forth and claimed.

In the drawings:

Fig. 1 is a view partly in section of the analyzing and controlling portion of a record card controlled sorting machine.

Fig. 2 is a detail of the card controlled contacts.

Figs. 3 and 3a are detailed views of one form of light control device which may be used with the present invention.

Fig. 4 is a detailed view of a commutator control device.

Figs. 5 and 5A show schematically a preferred form of the circuit connections to illustrate the principle of the invention.

Fig. 6 is a plan view of a standard counter unit.

It will be obvious from the description to follow that the present invention is applicable to many types of counting operations; however, it is preferred to describe the invention in conjunction with a record card controlled machine for the purpose of counting the individual records fed to the machine, and with the understanding that its application is not limited to the specific mechanism described.

One form of record card controlled machine to which the present invention is readily adaptable is the card controlled sorting machine, one type of which is disclosed and described in the U. S. Patent No. 1,969,362 issued to E. A. Ford, August 7, 1934. Referring now to Fig. 1, a brief description of the machine will be given. An electric motor 61 (Fig. 5) is provided to be connected to the main driving shaft 21 which in turn is connected to the card feeding rollers 22 and also to a shaft 23 on which is fixed a cam 24 adapted to move an arm 25 against the action of springs 26. The arm is pivoted at 27 and is connected at its upper end to a plate 28 provided with a card picker 29. The cam 24 moves the picker toward the left and the springs 26 acting against the arm 25 move the picker back toward the right. Each movement of the picker to the left causes the lowermost card in the stack 30 to be moved forward into cooperation with the first set of feed rollers 22. These rollers then feed the card to the next set of rollers. As the card is being fed from the first to the second set of rollers it passes under the electric sensing brush 31. The rollers then continue to feed the

card between the guide plates 38 and across the machine until it drops into one of the several sorting pockets 32. The cards fed from the stack 30 are provided with perforations at different index point positions which cooperate with the sensing brush 31 as the card is fed thereunder thereby energizing the magnets 33 to control the positioning of the guide blades 34. A shaft 35 also driven by the main shaft 21 and operating synchronously with the feeding of the cards is provided to carry the control cam disks 36. A disk is provided for each sorting pocket 32, and each disk is provided with a drop shoulder so that the said shoulder permits the corresponding guide blade 34 to drop at a time interval corresponding to the sensing of the corresponding index point position on the card. In other words, each of the cam disks 36 corresponds with one of the index point positions on the card. The "9" position passes under the sensing brush before any of the guide blades 34 has been dropped. If there is a perforation in the "9" position, a circuit is closed through the sensing brush 31 and cooperating contact roller 31a to energize the magnets 33 which are adapted to lock all the guide blades in their upper position. Then, when the card reaches the ends of the blades at 37 it will pass under all of the blades and be guided into the first pocket or "9" pocket. If there is no perforation in the "9" position but one in the "8" position, one of the cam disks 36 will permit one of the guide blades to be dropped just after the "9" position passes under the brush, and then when the "8" position having a perforation passes under the brush, the latter will close a circuit to energize the magnets 33 which then locks all the remaining guide blades in position, thus preventing any from dropping. Therefore, when the card reaches the guide blades, it will pass over the top of the lowermost blade and under the other blades and thus be guided into the second or "8" pocket. Sorting of the cards is effected similarly for those with perforations in other positions, so that the cards are guided to the individual pockets in accordance with the perforations disposed thereon.

The control circuits for the improved counting device will now be described, and it will be evident from the description that the circuits to be described can generally be employed in the desired applications and not limited to the specific application as shown in conjunction with the card controlled machine for the purpose of detecting the passage of a card by a given point or, in other words, initiating a control signal or impulse each time a card is fed to the machine for analysis.

Referring now to Fig. 2, means is provided, to 60 actuate a fast operating relay 39 upon the passage of each card through the machine, comprising a card lever 40 and contacts 41. The card lever is disposed adjacent to the sensing brush 31 and roller 31a, so that upon the passage of each card from the sensing station the card lever 40 is operated by the card passing through the guides 38 to close the associated contacts 41, thereby establishing a circuit from the terminals *a* and *b* including the relay 39. After the card has passed the lever 40, the contacts 41 are opened momentarily before the following card again causes them to be closed.

In Figs. 3 and 3a a different type of controlling circuit is shown to comprise a light sensitive device 42, such as a photo-cell, which is

suitably mounted on the frame 43 of the machine and connected to a standard amplifier 44, the output of which is connected to the fast operating control relay 39 referred to in the control circuit just described. The light sensitive device is controlled by any suitable light source as indicated at 45 which is mounted on a bracket 46 fixed to the frame of the machine. The shaft 23 (see Fig. 1) is extended beyond the frame 43 of the machine and to which is secured a hollow commutator-like housing 47 provided with an opening 48. The light source 45 is mounted within the housing which is rotated by the shaft 23 so that when the opening 48 is positioned between the light source and light sensitive device 15 the said device is operated by the light rays emanating from the source through the said opening and thereby causing the relay 39 to be operated. The said relay is adapted to be operated each time a card is fed past a predetermined point in the machine. In this modification, however, the card does not actuate directly the control means for the control circuit. The commutator housing 47 is adjusted so that the opening 45 permits the light rays to impinge upon the cell 42 shortly after the regular card lever contacts 49 have been operated, therefore until the said contacts are closed, the circuit from terminals *a* to *b* including the light source 45 remains open and consequently prevents the relay 39 to be energized. The operation of the card levers 49 is well known in record card controlled machines which are adjusted to be operated to maintain the associated contacts continuously closed as long as cards are successively fed to the machine. For a detailed description of such card levers, reference may be made to U. S. Patent No. 1,741,985, Figs. 2 and 6 therein and indicated at 219. Therefore, with cards passing through the machine, the contacts 48 are maintained in an operated position thus closing the circuit to the light source 45. Now, as the cards pass a selected position in the machine, the opening 45 is positioned between the energized light source and photo-cell energizing the cell 4 and relay 39.

In Fig. 4, the light source and photo-cell are replaced by a control disk 50 secured to the shaft 23, said disk provided with a conducting segment 51 adapted to engage the brushes 52. The conducting segment and brushes are adapted to be engaged as the card passes a predetermined point in the machine, so that when cards are fed to the machine, the control circuit for relay 39 is closed by both the card lever contacts 49 and the brushes 52 connecting relay 39 to the terminals *a* and *b*.

Referring now to Figs. 5 and 5A, a complete control circuit for the counting device is shown and includes two series of transfer relays which represent the units and tens orders as indicated. To simplify the drawings, the terminals *a* and *b* of the first control circuit described are shown connected to terminals *c* and *d* respectively. Before the description of the circuits of the counting device is given, the control circuits of the machine used to illustrate one of the applications of the invention shall be explained. These control circuits are well known and therefore need only be described briefly. For a detailed disclosure thereof, reference should be made to U. S. Patent No. 1,741,985.

Upon closure of the main switch *S* and upon depression of the start key 55, a circuit is established from one side of the line 56 through relays 7

58 and 59, through the stop key 60 to the other side of the line 57, energizing said relays. Energization of relay 58 provides current for the machine motor 61 through the contacts 58-a, which 5 upon operation is effective to feed cards to the machine as explained hereinabove. The start key must be held depressed until cards pass the regular card control contacts 49-a of the machine. These card contacts are similar to the 10 contacts 49 (described hereinbefore, see Figs. 3 and 4) and are adapted to be closed continuously until the card feeding is discontinued. With contacts 49-a closed, a holding circuit is established through the contacts 59-a and contacts 15 49-a to shunt the start key and thereby maintaining relays 58 and 59 and motor 61 operated, until the stop key 60 is depressed.

In addition to operating the contacts 49-a the cards operate the contacts 41 so as to close 20 and open momentarily upon the passage thereof to operate the relay 39 each time a card passes the said contacts. Energization of relay 39 causes the associated contacts 39-a (Fig. 5A) to be closed, thereby energization of the control 25 circuits of the units order of the counting device is effected to establish the following circuit: one side of the line 56 through contacts 39-a, normally closed contacts 10-g of relay 10, normally closed contacts 1-c, coil of relay 11, common conductor 62 and normally closed contacts 63-a of relay 63 (Fig. 5) to the other side of the line 57, energizing relay 11. Relay 1 is now energized by means of the established circuit from line 56, 30 through contacts 39-a which still remain closed, conductor 64, contacts 11-a, coil of relay 1 to the common conductor 62 and line conductor 57. The contacts associated with relay 1 are now operated; the contacts 1-b and 1-c are of the make before break type; that is, contacts 1-b 35 are closed before the contacts 1-c are opened. A holding circuit for relay 1 is provided through contacts 1-a as follows: one side of the line 56 to conductor 65, through the parallel circuit comprising contacts 20-c and contacts 10-b 40 to common conductor 66, resistance R-2, contacts 1-a, coil of relay 1, common conductor 62 to the other side of the line 57.

As long as the contacts 39-a remain closed, the coil of relay 11 is energized through the contacts 1-b and resistance R-1. The resistance R-1 is of such value that it will provide holding current for the relay 11; however, the value of this holding current is not sufficient to cause initial operation of the relay 11 (this statement 55 also applies to any one of the relays 11 to 20). The purpose of resistance R-2 in the holding circuit described is to prevent a potential holding circuit to be formed for the relay 11; for, with relay 11 still energized when relay 1 is energized, 60 the following circuit is possible: from conductors 56 and 65 to contacts 20-c and 10-b, conductor 66, resistance R-2, contacts 1-a, contacts 11-a, conductor 64, contacts 10-g, contacts 1-b, resistance R-1, coil of relay 11, common conductor 62 to the other side of the line 57. The resistance R-2, however, is of such value that whenever it is in series with resistance R-1 the current is limited to a value insufficient to maintain the relay 11 energized. Therefore, when the 65 contacts 39-a are opened, and this occurs after the relay 1 or like relay is energized and the holding circuit established therefor, the relay 11 is deenergized.

It will now be seen, upon initiation of the next 70 control impulse, namely due to the energization

of the relay 38 (the operation of which is indicative of another machine operation or cycle, in this instance, the passage of another card through the machine), a circuit is established to operate relay 2 of the chain of relays in the units order 5 and is effected as follows:

Closure of contacts 39-a permits the line 56 to be connected to conductor 64 and relay contacts 11-b, 1-d, 2-c, coil of relay 12, conductor 62 to the line 57, thus energizing relay 12. 10 Similarly, as just described, relay 2 is now energized through the operated contacts 12-a as follows: line 56, contacts 39-a now closed, contacts 11-b, 1-d, 12-a, coil of relay 2, common conductor 62 to the line 57. A holding circuit 15 is provided for relay 2 through the contacts 2-a as follows: line 56, conductor 65, parallel circuit through contacts 20-c and 10-b, conductor 66, resistor R-2, contacts 2-a, coil of relay 2, common conductor 62 to line 57. Operation of contacts 2-b connects resistor R-1 in series with contacts 1-d and coil of relay 12 thus preventing the operation of relay 12 when deenergized and upon initiation of a third control impulse which, due to the circuit arrangement, is also impressed upon contacts 2-b. For the same reason, relay 11 was not operated upon the initiation of the second control impulse which not only was impressed upon contacts 11-b but also on contacts 1-b through contacts 10-g, the current flow through the coil of relay 11 is limited by resistor R-1 associated therewith to the extent that energization of relay 11 cannot be effected. Upon decay of the control impulse relay 39 is deenergized and contacts 39-a are opened thus causing 35 relay 12 to be deenergized. Relay 12 is not maintained energized after opening of the contacts 39-a by the possible back circuit through the operated relay contacts due to the series relationship of resistances R-1 and R-2 associated 40 therewith, thereby reducing the current flow through the coil of said relay to a value less than the value of the holding current required by the relay. The circuit just referred to is the following: from line 56 to conductor 65, parallel circuit 45 through contacts 20-c and 10-b, conductor 66, resistor R-2, contacts 2-a, 12-a, 2-b, resistor R-1, coil of relay 12, common conductor 62 to line 57.

In a like manner, relay 3 is energized upon 50 initiation of the third control impulse and maintained energized by a holding circuit established through its associated resistor R-2 and contacts 3-a, relay 4 is energized upon initiation of the fourth control impulse, etc. and therefore 55 evident that the next relay in the chain or series is energized upon reception of the next impulse. Since relays 3 to 9 have similar control elements and circuits associated therewith as the relays 1 and 2 and operate in the same manner as the latter, it is believed further detailed description is 60 not necessary.

It was previously mentioned that a Veeder or other counter mechanism can be operated upon the reception of a predetermined number of impulses and for illustrative purposes let it be assumed that it is desired to operate the counter upon receipt of each tenth impulse in the relay chain. Switch 70 (Fig. 5A) therefore is closed in position (a) thereby providing a circuit to the 70 counter magnet 71 whenever contact 10-e is closed. In addition to operating the counter upon receipt of the tenth impulse, it is necessary to restore the previously energized relays in the chain, namely, 1 to 9, to their original normal po- 75

sition as shown in Fig. 5A so that upon initiation of the eleventh impulse, relay 1 will become energized in the manner as described.

Therefore, let it be assumed that relays 1 to 9, 5 have been energized and are maintained energized by the established holding circuits through the parallel circuit including contacts 20-c and 10-b. The circuit through which relays 10 and 20 will be energized is through a circuit established by the d contacts of the relays previously energized. For this reason, the circuit just mentioned must be maintained until the holding circuit for relay 10 is established; to accomplish this the contacts 10-a and 10-b are arranged 10 to be the make before break type. Now, assume that the tenth impulse is initiated, due to the momentary operation of relay 39 and contacts 39-a; the following circuit is established: line 56, contacts 39-a, conductor 64, contacts 11-b, 15 1-d, 12-b, 2-d, etc. to 19-b, 9-d to contacts 10-d, coil of relay 20, conductor 62, contacts 63-a to line 51, energizing relay 20. Contacts 20-a now connect the circuit just described from contacts 9-d to the coil of relay 10 to line 51, 20 energizing said relay. The relay 72 is not energized at this time because the contacts 39-c are opened whenever the control relay 39 is operated. The contacts 10-c and d are the make before break type and provide a holding circuit 25 for relay 20 through contacts 9-d, 10-c and resistor R-1 as long as relay 39 is operated. A holding circuit for relay 10 is also established as follows: from line 56, conductor 65, contacts 39-b now closed, conductor 73, resistor R-2, 30 contacts 10-a, coil of relay 10 to line 51. The contacts 10-b are now opened and since contacts 20-c are open the holding circuits for relays 1 to 9 are broken thus restoring the said relays to the normal inoperative position as shown 35 in the figure. Immediately, therefore, a supplementary holding circuit through contacts 7-g is established for relay 10. The said contacts are connected in parallel to the contacts 39-b which are now opened due to the deenergization of control relay 39. At this time, relay 20 is also deenergized to close the contacts 20-c. Reenergization of relays 1 and 11 is prevented during the interval of the tenth impulse and a holding circuit established therefor upon closure of contacts 20-c, by providing the contacts 10-g in 40 the control circuit, the last mentioned contacts are opened upon energization of relay 10 thus preventing faulty energization of relays 1 and 11.

Provision must be made to close the said control circuit upon energization of relay 10 because the contacts 10-g are maintained in an open position as long as relay 10 remains energized, which is a timed interval equivalent to the time required for the relay 7 to be energized to open 45 the contacts 7-g. Therefore, the control contacts 72-b are provided. Relay 72 is connected in parallel to relay 10 and therefore is energized by the holding circuit established for relay 10 whenever the contacts 39-c are closed. These 50 contacts are closed upon the decay of the tenth impulse and at that time relay 72 is operated to close the control contacts 72-b, and contacts 72-a which establish a holding circuit for the said relay. Relay 72 is deenergized when the 55 relay 10 is deenergized, thus the control circuit is conditioned for the reception of the control impulses either by contacts 10-g or 72-b. Upon reception of the eleventh impulse relays 11 and 1 are energized as described hereinabove 60 to establish successively series circuits so that

the following relay in the chain is energized upon initiation of the next control pulse.

It is understood that contacts 10-e are closed for the entire timed interval until relay 7 is reenergized by the seventeenth impulse. In this 5 manner, sufficient time is provided to permit the more sluggish and slower electromagnetic actuated counter indicated at 71 to be operated to enter one in the units order of the counter. Referring to Fig. 6, a typical and well known 10 counter unit is shown and it is believed mention need only be made of the fact that upon each 15 energization of the magnets 71, the units indicating wheel is positioned one step, and upon positioning from 9 to 0, a 1 is added in the tens 20 order in the usual manner, etc. Resetting of the counter is effected by a reset handle 75. For a detailed description of the counter unit, reference may be made to the U. S. Patent No. 2,043,295, wherein the magnets are indicated by 25 the reference character 56 and the reset handle by character 168.

To stop the operation of the machine, a stop key 60 is provided and assuming that the contact arm of switch 76 is positioned on contact a, 25 operation of the key opens the holding circuit to relays 58 and 59, deenergizing said relays and consequently the motor 61, thereby preventing further machine operations such as the feeding of cards. If it is desired to automatically stop 30 the machine upon completion of a tenth operation or multiple thereof, that is, immediately upon entry of a digit in the counter 71, the contact arm of switch 76 is positioned to engage contact b which is connected to a normally closed 35 contact 10-h operated by relay 10. It is evident, then, if the stop key 60 is operated, and let it be assumed at that moment a control impulse was initiated to operate relay 3, the motor circuit is not deenergized immediately, due to the 40 closed shunt circuit including contacts 10-h. The stop key is kept depressed until the tenth impulse or multiple thereof is effective to operate relay 10, thereby opening the contacts 10-h, thus preventing further feeding of the cards. 45

In the event the machine is stopped before the relay 10 has been operated to effect a visible entry into the counter 71, supplementary readout or indicating means should be provided to enable one to determine the exact number of 50 machine operations completed. The readout means may comprise a circuit as shown connecting the contacts 1-e, 2-e to 9-e in series whenever all the relays 1 to 9 are deenergized. Upon operation of the key 77 at this time the 0 55 indicating lamp 78 is energized. Connected to each f contact of the relays 1 to 9 is an indicating lamp 78 to identify the associated relay; thus upon operation of the key 77 when any one of the relays 1 to 9 is energized, the corresponding 60 indicating lamp is energized.

It may be necessary to provide more than one chain of counting relays when certain machine operations are counted at an extremely high rate of speed. Therefore, in Fig. 5, a second series 65 of relays are shown connected exactly as the relays in Fig. 5A and thus it is not necessary to describe further the operation of the second chain of relays except to state when the second chain is to be operated the switch 70 is placed in position (b) so that when the contacts 10-e are closed, the magnet 71 is not energized, but instead the control circuit 80 for the second series 70 of counting relays representing the tens order.

When two series of relays are connected in se- 75

ries by means of switch 70 as shown, it is necessary to provide an additional control relay such as indicated at 81, the purpose of which will be understood shortly. To permit the counter magnet 71 to be energized at the proper time switch 82 must be closed. Now let it be assumed that the tenth impulse has been transmitted to energize the relay 10 to establish the various circuits described hereinabove. Contacts 10-e are therefore closed and thus establish a circuit from one side of the line 56 to conductor 65, switch 70, contacts 10-e to conductor 80, coil of relay 81 to the other side of the line 57 through the contacts 63-b, and also by means of conductor 80 to contacts 110-g to the contacts c of relay 101, and coil of relay 111 and common conductor 83, contacts 63-b to the line 57 to energize the relays 111 and 81. Relay 101 is energized and maintained operated by the circuits established by operation of relay 111 exactly in the same manner as relay 1 which was described in detail hereinbefore and need not be repeated. Contacts 10-e remain closed for seven entries in the unit circuit until the contacts 7-g and 39-b are opened thus breaking the holding circuits for relay 10. Upon deenergization of relay 10, the relays 81 and 111 are deenergized. Relay 101 is maintained operated thus establishing a circuit to energize relays 112 and 102 upon the second operation of relay 10 closing the contacts 10-e for another interval of time equivalent to seven entries in the units order. In this manner, relays 102 to 110 are operated upon every tenth operation of the relay 10.

Let it be assumed that relays 101 to 109 are energized and that relays 1 to 9 are energized and that contacts 41 are now closed to energize the relay 39 thereby closing the contacts 39-a, 39-b, and opening the contacts 39-c, causing relay 10 to be energized closing the contacts 10-e which are then maintained in an operated position for seven entries in the units order. Closure of contacts 10-e at this time causes the relay 81 to be energized as described before closing its contacts 81-a and opening the contacts 81-b. Relay 120 is also energized through the circuit established by the contacts 110-g and the d contacts of relay 101 to 109. Upon energization of relay 120, through the contacts a of relay 120, the relay 110 is energized establishing a holding circuit through the contacts a of relay 110 and contacts 81-a as follows: one side of the line 56, conductor 84, contacts 81-a, conductor 85, resistor R-2, contacts a of relay 110, coil of relay 110, conductor 83, contacts 63-b to line 57. As mentioned in connection with relay 10, the adjustments of the contacts a to e of relay 110 are the same, thus the contacts a of relay 110 make before contacts b of relay 110 break. Therefore, the holding circuit for relay 110 is established before the contacts b of relay 110 open the holding circuits for relays 101 to 109, deenergizing said relays. It is seen that a parallel circuit is now established by contacts 81-a and contacts g of relay 107 to maintain relay 110 energized, so that upon deenergization of relay 81, the relay 110 is not deenergized.

The magnet 71 is energized to enter 1 upon the closure of contacts e of relay 110 through the following circuit: line 56, conductor 84, switch 82, contacts e of relay 110, conductor 86, coil of magnet 71 to line 57.

Now upon energization of relay 7 in the units order, relay 10 is deenergized, opening contacts 10-e, deenergizing relay 81. Relay 110, of course, remains energized until relay 107 is operated to open the contacts g of relay 107 to break the holding circuit for relay 110. Therefore, it is seen that contacts 110-g are opened as long as relay 110 remains energized. Closure of contacts 81-b now permits the relay 121, connected in parallel with relay 110, to be energized and establish a holding circuit therefore through the contacts 121-a. Operation of relay 121 also causes the contacts 121-b to be closed so that when the contacts 10-e are again closed, relay 101 can be energized as just described. The timing of operation of contacts 110-g and 121-b is different from the timing of operation of the contacts 10-g and 72-b. This change is necessary when the two chains of high speed relays are connected in series, otherwise faulty operation of relays 111 and 101 would be effected. It is evident if the contacts 121-b closed upon operation of relay 110 and the decay of the control impulse (operating relay 39), since contacts 10-e remain closed for seven entries, a faulty entry would be made by energizing the relays 111 and 101. For this reason, relay 121 is controlled by contacts 81-b which are operated by the extra control relay 81 rather than by the relay 39 as in the units order. Therefore, it is obvious that just by duplicating the chain of counting relays as shown in the units order and connecting the said chains of relays in series, an operative two-order chain relay counting device cannot be effected, instead a control circuit, as described, is necessary to change the timing of the operation of contacts 110-g and 121-b.

Similar indicating lamps are associated with the relays 101 to 109 so that the certain relays operated at a particular time can be indicated. Similarly to stop the counting device upon an even multiple number of operations, that is, immediately after entry in the indicating wheel type of counter, the contact arm of switch 76 can be positioned on contact c, so that upon operation of the stop key 60, the machine is not stopped until the contact 110-h is opened which is controlled by relay 110.

To reset the high speed relays to the normal inoperative position shown in the drawings, a reset key 90 is provided which upon operation energizes the relay 63 opening the associated contacts 63-a and b which, it is remembered, are included in the holding circuits for all the high speed relays 1 to 20 and 101 to 120, respectively.

If it is desired to extend the orders of the counter relays, a similar chain of relays for the hundreds order may be connected to switch 82 including a control relay similar to relay 81, just as the tens order of relays are shown connected to switch 70.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. A device of the character described comprising, in combination, a plurality of relays, a control circuit and means to energize said circuit successively, means to operate one of said relays upon energization of the circuit, means to operate

5 a second relay upon operation of the first mentioned relay, means to maintain the second relay operative and the first relay inoperative upon deenergization of the circuit, and means, including the latter relay after being set to the aforesaid inoperative position, for energizing a third relay upon energization of the control circuit a second time.

10 2. A device of the character described comprising, in combination, a plurality of relays, a control circuit and means to energize said circuit successively, means to operate one of said relays upon energization of the circuit, means under control of the last mentioned relay upon operation thereof for operating a second relay, means to maintain the second relay operative and render the first relay inoperative upon deenergization of the circuit, means to maintain the first relay inoperative upon the second energization 20 of the circuit, and means, including the latter relay after being set to the aforesaid inoperative position, for operating a third relay upon said second energization of the circuit.

25 3. A device of the character described, comprising in combination, a series of groups of relays, each group including a control relay and a companion relay, a control circuit for said series and means to energize the circuit, means to operate the control relay of one of said relay groups upon energization of said circuit, means effective upon operation of the control relay to operate a companion relay of the same group, means to maintain said companion relay energized and said control relay deenergized upon deenergization of 35 the control circuit, and means controlled by the operated relay group for causing the next group of the series to be operated under the control of said circuit.

40 4. A device of the character described, a plurality of sets of relays arranged to form a series, each set including a control relay and a companion relay, a control circuit for said relay series, means to impress impulses on said control circuit, means to cause the operation of one of said relay sets including means to energize the control relay thereof upon the occurrence of one such impulse, means controlled by the energized control relay for automatically operating a companion relay of the same set, means to maintain the latter relay energized while the first energized 45 relay is deenergized and maintained deenergized upon termination of the impulse, and means controlled by the condition of the relays of the operated set for causing the next set of relays 50 to be operated.

55 5. Apparatus of the character described comprising, in combination, an impulse circuit for emitting impulses, a series of relay devices, each with means responsive to the impulse circuit and

means controlled by the last-mentioned means for routing the next impulse to the next relay device, whereby the relay devices are operated successively by a succession of impulses, a work circuit operated under control of the relay devices upon the operation of a predetermined number of said devices, and means also under control of the relay devices to maintain the said work circuit in operated condition until a predetermined succession of said devices have again 10 been operated.

15 6. A device of the character described comprising, in combination, an impulse circuit for emitting impulses, a series of relay assemblies, each with means responsive to the impulse circuit and means controlled by the last-mentioned means for directing the next impulse to the next relay assembly, whereby the relay assemblies are operated successively by a succession of impulses, means to maintain portions of the energized relay assemblies in an operated condition upon the interruption of an impulse, a work circuit, means controlled by one of the relay assemblies for imparting and maintaining a control impulse to said work circuit after a predetermined number 20 of said relay assemblies have been energized and concomitantly rendering the maintaining means of the previously energized relay assemblies inoperative so as to deenergize said assemblies, and means under control of the relay assembly which 25 imparts the control impulse and another of said relay assemblies to prolong said impulse until a predetermined number of the deenergized relay assemblies are again operated.

30 7. A device of the character described comprising, in combination, an impulse circuit for emitting impulses, a series of relay organizations each having means responsive to the impulse circuit and means controlled by the last-mentioned means for routing the next impulse to the next 35 relay organization whereby the relay organizations are operated successively by a succession of impulses, means to maintain portions of said energized relay organizations in an operative condition upon interruption of an impulse, a work circuit, means under the control of one of the relay organizations to direct a control impulse to said work circuit after a predetermined number of said relay organizations have been 40 operated and concomitantly causing all of said operated relay organizations to become deenergized except the one which effects the control impulse, and means effective upon initiation of said control impulse and a preselected one of the deenergized relay organizations to prolong said 45 impulse until a certain number of said deenergized relay organizations are again operated.

JAMES W. BRYCE.
